(57) **CLAIM**

The ornamental design for a passively cooled and heated house, as shown and described.

DESCRIPTION

FIG. 1 is a front elevation view showing my new design.

FIG. 2 is a rear elevation view.

FIG. 3 is a right side elevation view; and,

FIG. 4 is a left side elevation view.

The broken line showing is included for the purpose of illustrating the environment and delineating the relative locations and positions of windows and doors, the specific features of which form no part of the claimed design.
